UNITED STATES PATENT OFFICE

167,875

BADGE

Marlon E. Wright, Waterbury, Vt.

Application May 15, 1952, Serial No. 19,721

Term of patent 14 years

(Cl. D29—2)

To all whom it may concern:

Be it known that I, Marlon E. Wright, a citizen of the United States of America, residing at Waterbury, county of Washington, and State of Vermont, have invented a new, original, and ornamental Design for a Badge, of which the following is a specification, reference being had to the accompanying drawing, forming a part thereof wherein:

Figure 1 is a front elevational view of a badge showing my new design.

Figure 2 is a top plan view of the same.

Figure 3 is a side elevational view of the same, and

Figure 4 is a rear elevational view of the same.

The dominant features of my design reside in those portions shown in full lines.

The star and the banner shown in solid lines are lined for the colors gold and blue, respectively.

I claim:

The ornamental design for a badge, as shown and described.

MARLON E. WRIGHT.
